UNITED STATES PATENT OFFICE

2,555,114

MANUFACTURE OF DERIVATIVES OF DISUBSTITUTED METHANE COMPOUNDS

Sheila Edith Bywater, Heston, and Gordon James Pritchard, Halewood, Liverpool, England, assignors to Ward, Blenkinsop & Company Limited, London, England, a British company

No Drawing. Application June 23, 1947, Serial No. 756,563. In Great Britain November 17, 1944

Section 1, Public Law 690, August 8, 1946
Patent expires November 17, 1964

13 Claims. (Cl. 260—433)

1 This invention is concerned with improvements in and relating to the manufacture of derivatives of disubstituted methane compounds, and it relates more particularly to the preparation of new derivatives of compounds of the general formula $R_1-CH_2-R_2$, (hereinafter referred to as "D. S. M. compounds") in which R_1 and R_2 , which may either be identical or different, are chosen from the residues of the following classes of substances:

A phenol sulphonic acid,
An alkyl phenol sulphonic acid,
A carboxyl phenol sulphonic acid,
A diphenyl or alkyl diphenyl mono- or disulphonic acid,
A benzene sulphonic acid,
A sulpho benzoic acid,
A naphthalene or alkynaphthalene mono- or disulphonic acid,
A naphthol or alkyl naphthol sulphonic acid, or
A nuclear substituted halogen, amino or nitro derivative of any of the above substances.

These D. S. M. compounds are substances of the synthetic tanning material type, and British Patent No. 547,564 describes the preparation for medical and like uses of substances prepared by combining D. S. M. compounds with bactericidal and/or physiologically useful organic bases or with the hydrate or oxide of one or more of the metals zinc, bismuth, copper and mercury so as to form salts. A further development of this work is described in British Patent No. 552,751 which discloses the preparation of silver and/or lead derivatives of D. S. M. compounds, these metals being known to possess antiseptic properties. The said prior specifications explain how substances prepared by combining a D. S. M. compound having tanning properties with a bactericidal or antiseptic component can be used advantageously for medical and allied purposes inter alia because the tanning action of the D. S. M. component enables the bactericidal or antiseptic component to be fixed and held in the skin or tissue.

We have now found that a further series of new and valuable derivatives of D. S. M. compounds can be produced by combining them with organometallic compounds of the undermentioned general formula.

Many of these organometallic compounds have valuable bactericidal, fungicidal, insecticidal or other useful properties, and we have found that by combining such compounds with D. S. M.

compounds products are obtained which have an extended field of usefulness compared with those of the products described in the said prior specifications and which can be used with advantage for many purposes, such for example as in agriculture, horticulture, the preservation of timber, in the textile industry, as well as in medicine and pharmacy.

According to the invention therefore we prepare new and useful products by treating a D. S. M. compound, as herein defined, with an organometallic compound having useful properties and of the general formula R_3MA , where R_3 is an alkyl, aryl, aralkyl or heterocyclic radicle which may or may not be substituted with neutral, acidic or basic substituents, M is a polyvalent metal, preferably mercury or arsenic, and A is an acidic radicle such as halide, nitrate, acetate or hydroxide or oxide or (when R_2 is basic or contains a basic substituent) an atomic grouping forming with M an acidic radicle and of such a nature that the compound will react with the D. S. M. compound, and irrespective of whether the said group is or is not split off in the process of the formation of the D. S. M. organometallic compound.

Whilst we do not desire to be limited by any theoretical explanations, it may be said that the reaction which occurs appears to be one of salt formation and this may as stated above occur either with or without elimination or splitting off of the group or element A . It is clear that the reaction can take place in several ways all falling within the scope of the invention. Thus, in the simple case of the example given below, it is probable that the reaction can be represented by the following equation, in which $R-SO_3H$ has been written for R_1 and R^1-SO_3H for R_2 in the general formula set out above:

It will be seen that in this case the group or radicle A is split off, but if R_3 were basic or had a basic substituent, as for example in the case of pyridyl group, the radicle A might or might not be split off.

If, for example R_3MA were pyridyl mercuric chloride, it is unlikely that the chlorine would be eliminated, at any rate completely, and the resulting reaction might be wholly or partly represented thus:

If, on the other hand, R_1MA were to be pyridyl mercuric acetate, it is probable that both reactions would occur, depending on the reaction conditions, such for example as pH.

In general it may however be said that the organometallic compound R_1MA should be one of basic function, which may, but need not necessarily, be centred on the metallic atom. In the cases of the stated mercury compounds, the basic function is centred on the M atom, but the use of other compounds such for example as an amino phenyl-arsonic acid, in which it is not so centred would of course also fall within the scope of the invention.

Whilst of course the invention comprises the production of the new substances in solid form, it is not limited to the carrying out of the reaction with stoichiometric proportions of the reaction components, and important advantages can, according to the invention, be secured by departing from such proportions.

It has hitherto been a drawback to the general use of organometallic compounds, particularly the aryl mercury compounds, that their solubilities in water and aqueous solutions, and in the commoner organic solvents are too low for satisfactory application of the compounds.

We have found that the new compounds are readily soluble, in an excess of the D. S. M. compounds from which they have been prepared, or in other D. S. M. compounds as well as in an excess of the parent sulphonic acids corresponding to R_1 and R_2 , and this property enables the new compounds to be prepared in the form of solutions, suitable for application either as such or after dilution with water if necessary.

In general we have found that a pH value of from 4-6.5 is usually advantageous, and this can conveniently be attained by a suitable adjustment of the quantities of the above-mentioned solubilising substances; it should however be noted that the use of other substances, such for example as mineral acids for the purpose of pH adjustment would not fall outside the scope of the invention.

The desired effect can be achieved either by first preparing the solid compound and then dissolving it in a suitable quantity of the selected solubilising agent or agents, so as to produce a solution of the desired strength and pH value, or the composition of the reaction mixture can be so adjusted as to yield a solution of the new compound after completion of the reaction, any necessary adjustment of pH value being subsequently carried out.

Accordingly the invention also comprises a method of manufacturing a solution of a D. S. M./organometallic compound prepared by the above mentioned method either in an excess of the same D. S. M. compound or in one or more of the following: Solutions of one or more D. S. M. compounds other than the one used for the preparation of the D. S. M./organometallic compound or of one or more of the acids corresponding to R_1 or R_2 either with or without the addition of one or more mineral acids.

The invention also comprises the adjustment of the pH value of such solutions to from 4-6.5.

In order to facilitate a better understanding of the invention, the following examples of how it may be carried out are given only as illustrations:

Example 1

1.37 parts by weight of phenyl mercuric hydroxide was boiled with water until solution was

complete, and to this was added, drop by drop, 3.8 parts by weight of the D. S. M. condensation product of naphthalene-2-sulphonic acid and formaldehyde (prepared by the method disclosed in British Patent No. 547,564) in 28% concentration. When the equivalent amount had been thus added a gelatinous precipitate was thrown down, and the solution was found to be acid to Congo red paper. At this stage the solution is unfilterable, but when a further 10% excess (0.38 part by weight) of D. S. M. compound had been added in the same way, the insoluble material coagulated and was separated and dried, yielding 1.1 parts by weight.

Per cent

Found, Hg..... 40.35
 $C_{33}H_{24}O_6S_2Hg_2$ the neutral salt requires
 Hg..... 40.9

$C_{45}H_{36}O_8S_2Hg_4$ the basic salt requires Hg..... 51.1

Alternatively 14.5 parts by weight of phenyl mercuric acetate (2 mol) was dissolved in 400 parts by weight of hot absolute alcohol; the solution was then treated with a little charcoal and filtered. To the hot alcoholic solution 26.5 parts by weight of the D. S. M. condensation product of naphthalene-2-sulphonic acid and formaldehyde in 35% concentration (1 mol) was added with stirring, a thick gelatinous precipitate separated which, after standing two hours, was filtered off and dried; yielding 8.2 parts by weight of the phenyl mercury complex. By concentrating the alcoholic mother liquors a further 5.9 parts by weight was obtained,

35 Found, Hg..... 44.0
 $C_{33}H_{24}O_6S_2Hg_2$ the true salt requires Hg..... 40.9
 $C_{45}H_{36}O_8S_2Hg_4$ the basic salt requires Hg..... 51.1

40 The compound with Hg 44% is consistently obtained and is evidently a complex corresponding to neither of the theoretical salts.

45 This phenyl mercury complex was a buff powder and dissolved to give a 13.5% solution in a 35% aqueous solution of bis-(naphthalene-2-sulphonic acid)-methane; this could be diluted without developing instability to form a solution containing 1% phenyl-mercury complex, with the pH adjusted to 4.0-4.5; this solution was then diluted 1000 times, the pH readjusted and the solution introduced into timber by the full cell process. The product was resistant to most of the common fungi.

50 In a similar manner the basic salt was isolated. 8.0 parts by weight of phenyl mercuric acetate (4 mols) was dissolved in 160 parts by weight of hot absolute alcohol, the solution was treated with a little charcoal and filtered, to the hot alcoholic solution 7.3 parts by weight of the D. S. M. condensation product of naphthalene-2-sulphonic acid and formaldehyde in 35% concentration (1 mol) was added, the phenyl mercury complex was thrown down, and after filtering and concentrating the alcoholic mother liquors a total of 6.0 parts by weight of the phenyl mercury complex was obtained.

Per cent

55 Found, Hg..... 51.2
 $C_{45}H_{36}O_8S_2Hg_4$ the basic salt requires Hg..... 51.1
 $C_{33}H_{24}O_6S_2Hg_2$ the true salt requires Hg..... 40.9

60 The basic phenyl mercury complex was a buff powder which dissolved to give a 0.5% solution in a 10% aqueous solution of either bis-(naphthalene-2-sulphonic acid)-methane, or naphthalene-2-sulphonic acid.

65 This solution without dilution was found to be

suitable for the impregnation of timber, using the empty cell process.

Example II

6.72 parts by weight of phenyl mercuric acetate was dissolved in 120 parts by weight of hot absolute alcohol and 17.9 parts by weight of 10.1% aqueous solution of bis-(phenol-4-sulphonic acid)-methane.

The phenyl mercury complex separated, and after the alcoholic solution had cooled, was filtered off and dried.

	Per cent
Found, Hg	53.4
$C_{25}H_{20}O_8S_2Hg_2$ (the neutral salt) requires Hg	43.8
$C_{37}H_{32}O_{10}S_2Hg_4$ (the basic salt) requires Hg	53.3

The phenol mercury complex was a buff powder, which dissolved to give a 0.5% solution in a 10% solution of either bis-(naphthalene-2-sulphonic acid)-methane or naphthalene-2-sulphonic acid.

Bis-(phenol-4-sulphonic acid)-methane was prepared by dissolving 34.8 parts by weight of phenol-4-sulphonic acid in an equal weight of water, 8.25 parts by weight of formaldehyde (40% solution) was introduced and the whole allowed to stand at room temperature for 24 hours. At the end of this time the reaction mass was diluted with 200 parts of water and warmed to 100° C. until all the formaldehyde was absorbed.

Example III

8.06 parts by weight of phenyl mercuric acetate was dissolved in 160 parts by weight of hot ethyl alcohol and 10.7 parts by weight of 16.5% aqueous solution of bis-(naphthalene-2:7-disulphonic acid)-methane prepared by the method disclosed in British Patent No. 547,564 added. The phenyl mercury complex separated and was filtered off and dried. 6.3 parts by weight of the complex was obtained.

	Per cent
Found, Hg	55.6
$C_{45}H_{32}O_{12}S_4Hg_4$ (the neutral salt) requires Hg	47.4

$C_{69}H_{56}O_{16}S_4Hg_8$ (the basic salt) requires Hg 55.8

The phenyl mercury complex was a yellowish powder which dissolved in a 10% solution of bis-(naphthalene-2:7-disulphonic acid)-methane to give a 0.5% solution.

Example IV

1 part by weight of ethyl mercuric acetate was dissolved in 40 parts by weight of hot ethyl alcohol and 1.05 parts by weight of anhydrous bis-(naphthalene-2-sulphonic acid)-methane, dissolved in 10 parts by weight of absolute alcohol added, a creamy gelatinous precipitate separated, which was washed with ether, and dried in *vacuo*. The ethyl mercury complex analysed as follows:

	Per cent
Found, Hg	46.5
$C_{25}H_{24}O_8S_2Hg_2$ (the neutral salt) requires Hg	45.3

$C_{29}H_{36}O_8S_2Hg_4$ (the basic salt) requires Hg 58.2

This ethyl mercury complex was a brown hygroscopic powder which dissolved in a 10% aqueous solution of bis-(naphthalene-2-sulphonic acid)-methane to give a 1% solution.

Alternatively a product, doubtless a mixture of the neutral and basic ethyl mercury complexes was obtained by dissolving 4 parts by weight of

ethyl mercuric acetate in 8 parts by weight of absolute alcohol and adding 5 parts by weight of a 35% aqueous solution of bis-(naphthalene-2-sulphonic acid)-methane. A sticky material separated which hardened on standing, this was filtered and dried, yielding 4 parts of the mercury complex.

	Per cent
Found, Hg	50.3
$C_{25}H_{24}O_8S_2Hg_2$ (the neutral salt) requires Hg	45.3
$C_{29}H_{36}O_8S_2Hg_4$ (basic salt) requires Hg	58.2

Example V

- 15 28.4 parts by weight of a 16% aqueous solution of the D. S. M. compound prepared by condensing 2-naphthol-6-sulphonic acid with formaldehyde (as disclosed in British Patent No. 547,564) was added to 6.72 parts by weight of phenyl mercury acetate dissolved in 120 parts by weight of hot absolute alcohol, the whole was then heated to boiling and filtered, on concentrating to half bulk 5 parts by weight of the phenyl mercury complex separated on cooling.
- 20 25

- Found, Hg 39.6
 $C_{33}H_{24}O_8S_2Hg_2$ (the neutral salt) requires Hg 39.6
 $C_{45}H_{36}O_{10}S_2Hg_4$ (the basic salt) requires Hg 50.1

- 30 The phenyl mercury complex was a reddish brown powder which gave 1.2% solution in a 10% aqueous solution of bis-(2-naphthol-6-sulphonic acid)-methane and a 0.6% solution in a 10% aqueous solution of bis-(2-naphthalene-2-sulphonic acid)-methane.

- 35 Alternatively 28.4 parts by weight of a 16% aqueous solution of the D. S. M. compound prepared by condensing 2-naphthol-6-sulphonic acid with formaldehyde was added to 13.5 parts by weight phenyl mercuric acetate dissolved in 140 parts by weight of hot absolute alcohol, the whole was heated to boiling and filtered and then evaporated to approximately half its bulk, on cooling 8 parts by weight of the phenyl mercury complex separated.

- 45 Found, Hg 51.0
 $C_{33}H_{24}O_8S_2Hg_2$ (the neutral salt) requires Hg 39.6
 $C_{45}H_{36}O_{10}S_2Hg_4$ (the basic salt) requires Hg 50.1

- 50 The phenyl mercury complex was a reddish powder which gave a 0.5% solution in either a 10% aqueous solution of bis-(2-naphthol-6-sulphonic acid)-methane or a 10% aqueous solution of bis-(naphthalene-2-sulphonic acid)-methane.

Example VI

- 55 60 65 4.52 parts by weight of 4-amino phenyl-arsenic acid was dissolved in 12.8 parts by weight of a 35% aqueous solution of bis-(naphthalene-2-sulphonic acid)-methane, the solution was then evaporated to dryness yielding 8.75 parts by weight of the arsenic complex, which was a brown powder

- 65 Found, As 17.3
 $C_{33}H_{32}O_{12}N_2S_2As_2$ requires 17.4

- 70 This complex dissolved in water to the extent of 1% and gave a clear amber solution. Before use the pH of the solutions was adjusted to 4-4.5.

Example VII

- 75 4.9 parts by weight of a 16% aqueous solution of the D. S. M. compound, prepared by condens-

ing 2-naphthol-6-sulphonic acid with formaldehyde, was evaporated to dryness on the water bath, and dissolved in 120 parts by weight of ethyl alcohol (74%), 2 parts by weight of ethyl mercuric acetate dissolved in 40 parts by weight of ethyl alcohol (74%) were added, and the whole evaporated to dryness.

Per cent

Found, Hg	56.5
C ₂₉ H ₂₆ O ₁₀ S ₂ Hg ₄ the basic salt requires Hg	56.9
C ₂₅ H ₂₄ O ₈ S ₂ Hg ₂ the neutral salt requires Hg	43.7

The ethyl mercury complex was a pinkish powder which dissolved to give a 0.6% solution in a 10% aqueous solution of either bis-(2-naphthol-6-sulphonic acid)-methane or 2-naphthol-6-sulphonic acid.

Example VIII

2 parts by weight of the pyridine addition compound of pyridyl mercuric acetate, was dissolved in 80 parts by weight of absolute alcohol, the solution was then treated with a little charcoal and filtered. To the hot alcoholic solution, 3.6 parts by weight of bis-(naphthalene-2-sulphonic acid)-methane was added with stirring. A precipitate came down, which after standing two hours, was filtered, washed with ether and dried at 110° C.

Per cent

Found, Hg	41.0
C ₃₁ H ₂₂ S ₂ O ₈ N ₂ Hg ₂ The neutral salt required Hg	40.8
C ₄₁ H ₃₂ S ₂ O ₈ N ₄ Hg ₄ The basic salt requires Hg	50.9

The pyridyl mercury complex was a white powder which dissolved to give a 1% solution in a 10% aqueous solution of bis-(naphthalene-2-sulphonic acid)-methane or a 0.6% solution in a 10% aqueous solution of naphthalene-2-sulphonic acid.

Example IX

Malachite Green zincichloride, bis-(naphthalene-2-sulphonic acid)-methane complex:

3.64 parts by weight malachite green zincichloride were dissolved in 120 parts by weight of hot ethyl alcohol and 3.21 parts by weight of the silver salt of bis-(naphthalene-2-sulphonic acid)-methane in 32 parts by weight of water added. The solution was left on the steam-bath for several hours to allow the silver chloride formed to coagulate and settle. The solution was then filtered and evaporated down in the presence of a small excess over the equivalent of zinc chloride.

Found: Zinc, 4.1%; nitrogen 3.8%; chlorine 4.4%.

Example X

Bis-(sulphosalicylic acid)-methane, phenyl mercury complex:

10.9 parts by weight sulphosalicylic acid was dissolved in 3.6 parts by weight of water by warming gently. 2.1 parts by weight of formaldehyde 40% was then added in three portions while heating on the steam-bath, and the heating continued for a total of 24 hours when the smell of formaldehyde had disappeared. A greyish-green paste was obtained which was taken up in water and filtered from a small quantity of insoluble matter, yielding a 15.04% solution of condensation product in the form of a pale straw-coloured liquid.

3.36 parts by weight of phenyl mercury acetate was dissolved in 120 parts by weight of absolute alcohol, and 14.85 parts by weight of the above 15.04% solution added and after warming for

some time the greyish powder was filtered off. This was found to contain 50.1% mercury.

On evaporation of the filtrate a second crop was obtained which contained 50.5% mercury.

Per cent

C₃₉H₂₈O₁₀S₂Hg₄ requires Hg----- 51.6

C₃₉H₃₂O₁₄S₂Hg₄ (=C₁₅H₁₀O₁₂S₂, 2C₆H₅Hg, C₆H₅HgOH) requires Hg----- 50.5

Example XI

Bis-(1-amino-8-hydroxy-3:6-naphthalene disulphonic acid) methane phenyl mercury complex:

6.1 parts by weight of pure acid sodium salt of 1-amino-8-hydroxy-naphthalene-3:6-disulphonic acid was suspended in 50 parts by weight of cold water and 2 parts by weight concentrated hydrochloric acid added. The mixture was filtered and washed free from chlorides and suspended in 25 parts by weight of water, and 3 parts by weight of formaldehyde 40% added. The colour changed slowly from a grey-green sludge to bright yellow and on standing overnight, to a deep orange clear solution. This was heated on the steam bath until the odour of formaldehyde disappeared (several hours) and evaporated to dryness. 5.4 parts glistening deep red scales were obtained. 1.62 parts of this condensation product (by weight) were dissolved in 760 parts by weight 50% ethyl alcohol and the mixture with 3.36 parts by weight of phenyl mercury acetate in 60 parts by weight absolute alcohol heated to boiling and filtered from a slight residue. It was then evaporated on the steam-bath and a reddish powder separated out which was found to contain 42.7% mercury.

Per cent

C₄₃H₃₄O₁₄N₂S₄Hg₄ requires Hg----- 45.7

C₄₅H₃₈O₁₆N₂S₄Hg₄ requires Hg----- 44.7

Example XII

Bis-(naphthalene-2-sulphonic acid) methane, benzyl mercury complex:

2 parts by weight benzyl mercury chloride was dissolved in 160 parts by weight absolute alcohol. To this was added freshly precipitated silver oxide (from 2.8 parts by weight silver nitrate and 48 parts by weight sodium hydroxide).

The suspension was stirred and refluxed for 8 hours until a few drops on filtering showed no trace of chloride. The solution was then filtered hot and 2.63 parts by weight of bis-(naphthalene-2-sulphonic acid)-methane solution, 49.7% w/w, added to the filtrate. After several hours the gelatinous mass was filtered at the pump and dried.

Found: Hg=39.9%.

We claim:

1. As a new compound the bis-phenyl mercury derivative of bis-(naphthalene-2-sulphonic acid)-methane.

2. A method of manufacturing useful products which comprises reacting a compound of the general formula R₁-CH₂-R₂ with an organometallic compound of the general formula R₃MA where R₁ and R₂ each represents a monovalent radical selected from the group consisting of

—C₆H₅(OH)(SO₃H), —C₆H₅(OH)(SO₃H)(alkyl),
 —C₆H₂(OH)(SO₃H)(COOH), —C₆H₈(SO₃H),
 —C₁₂H₇(SO₃H)₂, —C₁₂H₇(SO₃H)(alkyl),
 —C₁₂H₆(SO₃H)₂(alkyl), —C₆H₅(SO₃H),
 —C₆H₅(SO₃H)(COOH), —C₁₀H₆(SO₃H), —C₁₀H₅(SO₃H)₂,
 —C₁₀H₅(SO₃H)(alkyl), —C₁₀H₄(SO₃H)₂(alkyl),
 —C₁₀H₅(OH)(SO₃H), —C₁₀H₄(OH)(SO₃H)(alkyl)

and said radicals in which a ring hydrogen atom 75 is substituted by a member of the group con-

sisting of a halogen atom, an amino group and a nitro group, R₃ is a radical selected from the group consisting of alkyl, aryl, aralkyl and heterocyclic radicals and alkyl, aryl, aralkyl and heterocyclic radicals having a substituent with a neutral reaction, M is a metal selected from the group consisting of mercury and arsenic and A is a member of the group consisting of acid radicals and groupings forming acid radicals with M.

3. The method defined in claim 2 in which the reaction is carried out with an excess of the compound R₁CH₂R₂.

4. The method defined in claim 2 in which M is mercury.

5. As new compound salts formed by reacting compounds of the general formula R₁—CH₂—R₂ with an organometallic compound of the general formula R₃MA where R₁ and R₂ each represents a monovalent radical selected from the group consisting of:

—C₆H₅(OH)(SO₃H), —C₆H₅(OH)(SO₃H)(alkyl),

—C₆H₅(OH)(SO₃H)(COOH), —C₁₂H₈(SO₃H),

—C₁₂H₇(SO₃H)₂, —C₁₂H₇(SO₃H)(alkyl),

—C₁₂H₆(SO₃H)₂(alkyl), —C₆H₅(SO₃H),

—C₆H₅(SO₃H)(COOH), —C₁₂H₇(SO₃H)₂,

—C₁₀H₅(SO₃H)(alkyl), —C₁₀H₄(SO₃H)₂(alkyl),

—C₁₀H₄(OH)(SO₃H), —C₁₀H₄(OH)(SO₃H)(alkyl)

and said radicals in which a ring hydrogen atom is substituted by a member of the group consisting of a halogen atom, an amino group and a nitro group, R₃ is a radical selected from the group consisting of alkyl, aryl, aralkyl and heterocyclic radicals and alkyl, aryl, aralkyl and heterocyclic radicals having a substituent with a neutral reaction, M is a metal selected from the group consisting of mercury and arsenic and A is a member of the group consisting of acid radicals and groupings forming acid radicals with M.

6. A method as defined in claim 2 in which R₃ is an aryl radical.

7. A method as defined in claim 2 in which R₃ is an aralkyl radical.

5 8. A method as defined in claim 2 in which R₃ is a heterocyclic radical.

9. A method as defined in claim 2 in which R₃ is an aryl radical having a substituent with a neutral reaction.

10 10. A new compound as defined in claim 5 in which R₃ is an aryl radical.

11. A new compound as defined in claim 5 in which R₃ is an aralkyl radical.

12. A new compound as defined in claim 5 in which R₃ is a heterocyclic radical.

13. A new compound as defined in claim 5 in which R₃ is an aryl radical having a substituent with a neutral reaction.
